UNITED STATES PATENT OFFICE.

KURT WANDEL, OF NEW YORK, N. Y., ASSIGNOR TO SAFEPACK MILLS, OF BOSTON, MASSACHUSETTS, A CORPORATION OF MASSACHUSETTS.

REINFORCED TUBE AND BAG MAKING MACHINE.

1,382,579.

Specification of Letters Patent. Patented June 21, 1921.

Application filed December 13, 1918. Serial No. 266,545.

To all whom it may concern:

Be it known that I, KURT WANDEL, a citizen of Wurtemburg, who have declared my intention of becoming a citizen of the United States, and resident of New York, county of New York, State of New York, have invented an Improvement in Reinforced Tube and Bag Making Machines, of which the following description, in connection with the accompanying drawings, is a specification, like characters on the drawings representing like parts in each of the several views.

This invention relates to apparatus for producing rapidly and continuously a tubular formation suitable for making bags and the like, from sheet material such as pitch coated paper and with threads or filaments applied thereto in a manner so as to reinforce the tubular form either lengthwise or crosswise or both. A principal object of the invention is to provide means which I believe to be broadly new to produce by a continuous operation a tube of non-self sustaining material spirally wound. A further object is to provide means whereby such a tubular form may be continuously produced of indefinite length and if desired made into a roll. A further object is to provide mechanism whereby a plurality of sheets of non-self sustaining material may be wound into tubular form with one sheet superposed over another, provision being preferably made for cementing said layers together with water-proofing pitch or the like. A further object is to provide means whereby reinforcing yarns or filaments may be applied to a tubular form produced as stated in the manufacture thereof for strengthening the same either lengthwise or crosswise or both. A still further object is to provide means whereby a tubular form of indefinite length may be produced by a continuous operation and at a relatively rapid rate without requiring the operation at excessive speed of either the paper or the spool carriers or any other moving part. To these ends I provide a rotating mandrel having means co-operative therewith for the winding thereon spirally of one or more layers of sheet material to form a tube with means for continuously drawing the tube so formed endwise off the mandrel and preferably also spool carriers associated with said mandrel in a manner to supply yarns or filaments to the paper tube thereon to extend either crosswise or length-

wise thereof or both lengthwise and crosswise. The foregoing and other objects and advantages of the invention will more fully appear from the following detailed description, and the distinctive features of novelty 60 will be pointed out in the appended claims.

Referring to the drawings:

Figure 1 is a plan view with parts in section showing an apparatus constructed in accordance with my invention; 65

Fig. 2 is a partial side elevation showing the delivery end of the mandrel;

Fig. 3 is an end view thereof;

Fig. 4 is a diagrammatic section on line 4—4 of Fig. 1 showing a coating station; 70

Fig. 5 is a partial transverse section of the rotating mandrel;

Fig. 6 is a sectional elevation showing enlarged the winding-on mechanism;

Fig. 7 is a similar sectional elevation of 75 the winding-on mechanism taken at right angles to Fig. 6;

Fig. 8 is a front end view of the winding-on mechanism;

Fig. 9 is a sectional detail on line 9—9 of 80 Fig. 8;

Fig. 10 is a rear end view of the winding-on mechanism;

Fig. 11 is an enlarged detail elevation showing a mechanical movement adapted 85 for controlling the winding-on movement;

Fig. 12 is a fragmentary elevation further illustrating the operation of the movement of Fig. 11;

Fig. 13 is an enlarged transverse section on line 13—13 of Fig. 1, and Fig. 14 is a fragmentary sectional view showing a portion of the driving connections. 90

In suitable spaced apart bearing framework posts or standards 1, 2 a stout shaft 95 3 is fixed having journaled on a projecting end thereof a long cylindrical mandrel 4 which is supported wholly by said shaft and with its outer extremity tapered off as indicated at 5 to a thin edge 6. The mandrel 4 is constantly rotated in any suitable manner as by a sprocket and chain connection 7 from a prime drive shaft 8 mounted in suitable framework bearings 9 and shown as equipped with usual driving pulleys 10. A 100 paper web W is supplied for winding spirally on the mandrel 4 from a roll 11 mounted diagonally with respect to the mandrel 4 and as shown constituting part of a pitch coating station where the outer sur- 110

face of the paper as it is wound on the mandrel is previously coated with pitch from a pitch applying roll 12 which receives hot pitch from a pitch roll 13 in a heated pitch tank 14 as is usual. The disposition of the coating station and roll 11 with respect to the mandrel 4 is preferably such that the spiral winding overlaps to some little extent as indicated at O. For supplying a series 10 of spaced apart threads or filaments to extend lengthwise of the tube as it is formed, I provide a carrier 15 mounted for rotation in a ring bearing 16 which encircles said carrier. The carrier 15 is preferably and as 15 shown of stepped formation so as to permit the mounting thereon of a maximum number of spools S permitting the yarns or filaments to be spaced as closely together as may be desired. Connections are provided 20 for rotating the spool carrier 15 in the same direction as the mandrel 4 and preferably at the same rate of speed so that the threads as given out therefrom will extend straight lengthwise of the mandrel. For this purpose the prime drive shaft 8 is connected to 25 drive a countershaft 17 mounted adjacent thereto and in parallelism therewith through spur gearing 18 with an interposed intermediate gear 18^a so that the shaft 17 is turned 30 in the same direction as the shaft 8 and at a considerably higher rate of speed, the larger gear of the gear train 18 being fixed on the shaft 8. The shaft 17 through spur 35 gearing 19 including an intermediate gear 19^a engages a ring gear 20 on the carrier 15 to rotate the same, the described gear connections including the sprocket drive 7 being so proportioned that the carrier 15 will thus be turned at the same rate as the mandrel. 40 The carrier 15 has fixed thereto a guide ring 21 equipped with a series of spaced apart 45 passages through which the threads are guided and given out from the respective spools, this guide ring encircling and lying relatively close to the periphery of the mandrel 4 so that the threads are thus held to be laid in parallelism and straight lengthwise of the mandrel onto the paper tube as it is drawn lengthwise off the mandrel as presently described. In advance of the carrier 50 15 I mount for rotation a second spool carrier 22 in a ring bearing mounting 23. This carrier is equipped with a ring gear 24 with which meshes a relatively large gear 25 fixed on the shaft 17 whereby the carrier 22 is driven in a direction opposite to the direction of rotation of the mandrel and of the carrier 15 and at a relatively high rate of speed. This carrier is equipped with a plurality of spools S' which may be varied in 55 number according to the spacing desired of the transverse threads that are wound to encircle the tube as it is formed. From the spools S' the threads are led through passages of a guide ring 26 fixed to the carrier 60 22 relatively close to and in advance of the ring 21. Thus the threads from the spools S' will be wound continuously around the pitch coated surface of the paper tube as it is drawn along, in spiral paths which are 65 made to approximate more nearly a direction straight transverse of the tube by the combined action of the rotations in opposite directions of the mandrel 4 and the carrier 22 with respect to each other. I preferably apply to the paper tube thus constituted another layer of paper also wound spirally. For this purpose a second paper web W' is delivered from a suitable source 70 of supply arranged diagonally with respect to the mandrel this being shown as a second coating station 27 similar to the station 11 but which is arranged to coat the under surface of the paper web as it is wound on to the mandrel. For operating the rolls of the 75 coating stations 11, 27 I show connections from the prime drive shaft 8 consisting in bevel gearing 28 driving a transversely extending flexible shaft 29, the other end of which is connected by bevel gearing 30 to 80 the operative rolls at the station 27 while a sprocket and chain connection 31 leads therefrom to a shaft extension 32 from the rolls of the coating station 11. The delivery end 5 of the mandrel is formed to change 85 gradually from a cylindrical cross section to the extended edge extremity 6 in a manner so that the perimeter thereof remains substantially constant and hence the completed tube as it is drawn off the mandrel will 90 be changed from a circular section to a flattened out one without wrinkling or mutilation. In accordance with my invention means is provided adjacent the mandrel extremity 6 to draw the tube constantly off the 95 mandrel at a rate proportional to the production thereof by the described spiral winding. For this purpose a rotating frame work 33 is provided, mounted to turn in spaced apart ring bearings 34 and equipped 100 with a ring gear 35 which is engaged through an intermediate with a gear 36 fixed on the end of the shaft 8, these gear elements being so proportioned that the frame 33 will be rotated in precise unison with the 105 mandrel. The outer one of the stationary bearing mountings 34 has fixed thereto an internal ring gear 37 with which meshes constantly a gear 38 fixed at the end of a shaft 39 journaled lengthwise of and adjacent one side of the frame 33 whereby the gear 38 carried thereby will describe an orbital path and always keep in mesh with the stationary ring gear 37 so that it and the shaft 39 will be driven thereby as the 115 frame 33 rotates. The shaft 39 through bevel gearing 40 drives a pair of rolls 41 intergeared as seen as 42 mounted at the front end of the frame 33 so that the receiving mouth between said rolls is diametrical 120 125 130

of the frame 33 and in line with the delivery edge 6 of the mandrel. I preferably provide means whereby these rolls which receive between them and press the flattened tube, are adjustable toward and from each other according to varying thicknesses of stock which may be handled to produce the tube. For this purpose the shafts 41^a of these rolls are mounted in bearing blocks 5 41^b slidably mounted in a housing 33^a of the frame 33 and acted on by a compression coil spring 43 which normally tends to press said bearing blocks apart. One of these bearing blocks is acted on from its outer 10 side by an adjustable wedge member 44 the adjustment of which by a nut 44^a thereon acts to press the rolls toward each other to a predetermined extent, it being of course understood that such adjustable mounting is 15 employed at each end of this pair of rolls. A take-on mandrel 45 for the completed tube T is detachably mounted between a driving arbor 46 and a tailstock arbor 46^a transversely central and diametrical of the 20 frame 33. This mandrel is driven by means of a friction disk 47 rigid with the arbor 46, this disk having an outer friction face which is engaged by an adjustable friction disk 48 25 slidably keyed on a shaft 49. The shaft 49 is journaled at its ends in bracket members 30 50, 51 journaled to swing on the shaft 39 and it has fixed at one end thereof a gear 52 which is driven by a pinion 53 fixed on the shaft 39. The friction disk 48 is held 35 pressed against the face of the disk 47 by tension springs 48^a anchored to the frame 33 and engaged with the outer end of the brackets 50, 51. Thus the take-on mandrel 45 will be driven at a rate determined by 40 the radial distance of the driving friction disks 48 from the driven disk 47. Since it is requisite that the take-on mandrel 45 be rotated at a progressively lower rate as the roll of tube thereon increases in diameter, 45 means is provided whereby the friction disk 48 is shifted automatically gradually outward with respect to the axis of disk 47 in the operation of the machine. For this purpose the disk 48 has a grooved neck 49^a engaged by a shipper bracket 54 having a nut 50 portion 54^a engaged by a threaded shaft 55 which is journaled at its ends in the bearing brackets 50, 51. The shaft 55 has fixed to a 55 projecting end thereof a ratchet wheel 56 equipped with a handle 56^a for manual operation when desired. This ratchet wheel which is thus carried eccentrically of the frame 33 is engaged at every rotation of the frame 33 by a pawl 57 acted on by a spring 60 57^a pivoted to a bracket 58 secured to a bar 34^a fixed to the ring bearings 34 and constituting therewith a stationary frame structure. Thus the pawl 57 striking the ratchet wheel 56 will move the disk 48 radially outward of the disk 47 step-by-step at each ro- 65 tation of the frame 33 and to an extent so that the peripheral speed of the roll as it is built up on the mandrel 45 will be substantially constant. Since for the different characters and thicknesses of the tube stock, the 70 roll of completed tube on the mandrel 45 will build up with varying degrees of rapidity, I provide means whereby the rate of radial movement of the disk 48 with respect to the disk 47 may be varied as required. 75 For this purpose an adjustable guard member 59 is provided and secured to the bracket 50 adjacent the ratchet wheel 56 by a bolt and slot clamp 59^a. The pawl 57 is equipped with a roll 60 near its outer end adapted to 80 engage on the guard member 59 and lift the pawl 57 out of engagement with the ratchet wheel 56 after a predetermined extent of actuation thereof. Thus by shifting the guard member 59 the pawl is caused to 85 actuate the ratchet wheel to a greater or less extent at each operative movement and thus vary the feed impulse imparted to the disk 48 according to requirements. 90

In accordance with my invention the periphery of the mandrel 4 is preferably serrated or ribbed lengthwise thereof as indicated at 4^a, presenting thus a spaced apart series of parallel edges around which the paper and threads are successively wound. 95 This contributes to the ease and readiness with which the paper tube is drawn endwise along the mandrel, by reason of reduced frictional area and it is also a feature of value and importance for the reason that the 100 initial paper winding will be to some extent "draped" or festooned over these edges as indicated at p in Fig. 5 and thus a certain yield or capacity for outward "give" is imparted, which throws the major portion of 105 stress on the reinforcing threads or filaments f in use, i. e., the paper is protected from premature breaking stresses by the full reinforcing action of the filaments. I consider this a feature of value and importance since 110 in the use of paper reinforced by yarns or filaments heretofore it has been difficult to tension the threads relatively with respect to the paper so that the threads would bear their proper share of resistance to stresses, it 115 being generally the case that the paper being initially taut would break before any considerable part of the stress was taken up by the reinforcing filaments. The operation 120 of the mechanism will be readily understood without further detail description. The described gearing carried by the rotating frame 33 is so proportioned as to turn the rolls 41 and the take-on mandrel 45 at just the correct rate to draw the completed tube 125 continuously off the mandrel as fast as it is produced thereon by the spiral winding arrangement described, it being understood that the rolls 41 serve as feeding or drawing rolls as well as flattening rolls for the tube. 130

It will be understood that any suitable means (not shown) may be employed for tensioning the spools S and S' so that the threads therefrom will be drawn out under a proper 5 degree of tension, which however for the present purposes need not be great. While I herein show the tubular form as made up of two superposed spiral layers in overlapping relation, it will be understood that this is 10 merely illustrative of a more comprehensive form and that the tube may be made up of either a single spiral winding or any plurality thereof as desired. Likewise while I prefer to employ means as described for 15 applying lengthwise and transverse encircling yarns or filaments to reinforce the tube, in a broader aspect these are optional and either the means for applying the lengthwise threads or the encircling threads, or both 20 may be dispensed with should the product sought not require such reinforcing elements. Likewise while I show herein one spool carrier as rotatable in synchronism with the mandrel and the other spool carrier rotatable 25 in the opposite direction, this also is to be understood in a broader aspect as merely illustrative of spool carrier means, which may be either stationary with respect to the mandrel or movable in either direction with 30 reference thereto according to whether it is desired to have the threads laid straight lengthwise of the tube or approximately straight crosswise, or at varying spiral angles. I therefore desire the present embodiment to be considered in all respects as illustrative and not restrictive, reference being had to the appended claims rather than to the foregoing description to indicate the 35 scope of the invention.

40. Having described my invention, what I claim as new and desire to secure by Letters Patent is:

1. A machine for making non-self-sustaining tubes, comprising a mandrel mounted 45 for rotation, and having means associated therewith for winding a web spirally thereon to form a continuous tube, means for flattening the tube and means for packing the flattened tube.
50. 2. A machine for making non-self-sustaining tubes, comprising a mandrel mounted for rotation having means associated therewith for winding a paper web spirally thereon to form a continuous tube, and 55 means for continuously drawing such tube endwise off the mandrel in a flattened condition.
60. 3. A machine for making non-self-sustaining tubes, comprising a mandrel mounted for rotation having means associated therewith for winding a paper web continuously thereon with edges overlapping, said means including a coating station, and means connected for movement in timed relation with the movement of said mandrel 65

for continuously drawing off the tube therefrom in a flattened condition.

4. A machine for making non-self-sustaining tubes, comprising a mandrel mounted for rotation having means associated therewith for winding a paper web continuously thereon with edges overlapping, said means including a coating station, and means connected for movement in timed relation with the movement of said mandrel 70 for continuously drawing off the tube therefrom and flattening the same, said means having provision for winding the flattened tube into a roll.

5. A tube making machine, comprising a 80 cylindrical mandrel mounted for rotation, said mandrel having a delivery end changing gradually to an extended edge with a substantially constant perimeter, and means associated with said mandrel for winding 85 a web spirally thereon with overlapping edges to form a continuous tube.

6. A tube making machine, comprising a mandrel mounted for rotation having means associated therewith for winding a paper 90 web spirally thereon to form a continuous tube, means for drawing the tube continuously off said mandrel, and means for continuously applying reinforcing filaments to the tube as it is formed. 95

7. A tube making machine, comprising a mandrel mounted for rotation having means associated therewith for winding a paper web spirally thereon to form a continuous tube, means for drawing the tube continuously off said mandrel, and means for continuously applying reinforcing filaments to the tube as it is formed, said means constructed and arranged to apply a series of filaments spaced apart around the periphery of the 100 tube to extend lengthwise thereof.

8. A tube making machine, comprising a mandrel mounted for rotation having means associated therewith for winding a paper web spirally thereon to form a continuous 110 tube, means for drawing the tube continuously off said mandrel, and means for continuously applying reinforcing filaments to the tube as it is formed, said means constructed and arranged to apply filaments 115 transversely encircling said tube.

9. A tube making machine, comprising a mandrel mounted for rotation having means associated therewith for winding a paper web spirally thereon to form a continuous 120 tube, means for drawing the tube continuously off said mandrel, and means for continuously applying reinforcing filaments to the tube as it is formed, said means having one portion constructed and arranged to 125 apply filaments in spaced apart relation around the tube to extend lengthwise thereof, and another portion to apply filaments encircling said tube.

10. A tube making machine, comprising a 130

mandrel mounted for rotation and having means associated therewith for producing a tube thereon continuously and drawing off the same, and a thread carrier mounted for 5 rotation around said mandrel to apply reinforcing filaments to the tube as it is formed.

11. A tube making machine, comprising a mandrel mounted for rotation and having means associated therewith for producing a 10 continuous tube thereon and drawing off such tube, and a thread carrier encircling said mandrel and connected for rotation in synchronism therewith equipped with means to apply threads in spaced apart relation 15 around the tube on said mandrel.

12. A tube making machine, comprising a mandrel mounted for rotation and having means associated therewith for producing a continuous tube thereon and drawing off 20 such tube, and a thread carrier encircling said mandrel and connected for rotation in opposite directions with respect thereto for applying threads to encircle the tube.

13. A tube making machine, comprising a 25 mandrel mounted for rotation having means associated therewith for coating a web and winding the same spirally on said mandrel to form a continuous tube, and means for winding a second web spirally on the tube 30 so formed to reinforce the same, and means to draw off the tube continuously in a flattened condition.

14. A tube making machine, comprising a mandrel mounted for rotation having means 35 associated therewith for coating a web and winding the same spirally on said mandrel to form a continuous tube, means for applying reinforcing filaments continuously to the tube as it is formed, and means for 40 winding a second web spirally on the tube so formed.

15. A tube making machine, comprising a mandrel mounted for rotation having means associated therewith for winding a web 45 spirally thereon to produce a continuous tube, and means for continuously drawing off

the tube from said mandrel including a winding-on mandrel extending transversely of the first named mandrel and mounted and connected for rotation on its own axis and 50 also to turn bodily in synchronism with the first named mandrel.

16. A tube making machine, comprising a mandrel mounted for rotation having means associated therewith for producing a tube 55 continuously thereon, and means for drawing such tube off the mandrel consisting in a winding-on roll mounted and connected for rotation and equipped with means for varying the rate of such rotation automatically 60 and progressively as the tube roll is wound thereon.

17. A tube making machine, comprising a mandrel mounted for rotation having means associated therewith for producing a tube 65 continuously thereon, and means for drawing such tube off the mandrel mounted and connected for bodily movement in synchronism with the mandrel and including a winding-on mandrel having a driving connection 70 with elements automatically and progressively shiftable by definite degrees to vary the rate of rotation of said mandrel as the tube roll is wound thereon.

18. A tube making machine, comprising a 75 mandrel mounted for rotation having a serrated periphery, means for winding a web spirally thereon to form a continuous tube, and means for applying reinforcing filaments to the tube as it is formed on said 80 mandrel.

19. A tube making machine, comprising a mandrel presenting a series of lengthwise extending edges, means for winding a web 85 spirally thereon to form a continuous tube, means for applying reinforcing filaments to the tube as it is formed, and means for continuously drawing off the tube so formed.

In testimony whereof, I have signed my name to this specification.

KURT WANDEL.
